UNITED STATES PATENT OFFICE.

ARCHELUS H. MITCHELL, OF SELMA, ALABAMA.

ANESTHETIZING AND RESUSCITATION APPARATUS.

1,236,591.

Specification of Letters Patent. Patented Aug. 14, 1917.

Application filed July 21, 1916. Serial No. 110,430.

To all whom it may concern:

Be it known that I, ARCHELUS H. MITCHELL, a citizen of the United States, residing at Selma, county of Dallas, State of Alabama, have invented a new and useful Anesthetizing and Resuscitation Apparatus, of which the following is a specification.

My present invention consists of a novel anesthetizing and resuscitation apparatus 10 wherein any form of inhalation anesthetic may be administered and also forms a resuscitation apparatus and is provided with a mercury manometer forming a safety attachment. 15 In my present invention the administration of ether or chloroform vapor or nitrous oxide oxygen anesthetics or their several combinations is provided for, and the desired percentages obtained by pressure 20 gages or by wash bottles employed, either together or separately, whereby if one device for the estimation of the percentage of gas administered fails, the other device may be used separately without interrupting 25 the anesthesia.

In case of suspended respiration and animation the respiration of the patient can be carried on with the same apparatus as used in anesthesia by employing oxygen or 30 air or any percentages of these.

It further consists of a novel device of the character stated, wherein the gas tanks may be changed as they are emptied with absolutely no loss of gas and without interrupting the anesthesia. 35

Any desired amount of air may be added to the gas mixture through the automatic or foot pump without any adjustment of the face piece or without any attachment on 40 the face piece for such purpose. Air can be given to the patient in place of anesthetic without the removal of the face piece or any adjustment of it thus allowing the patient to come as nearly out from the anesthetized condition as desired and then without any change of the various anesthetic mechanism, anesthesia may again be commenced at will. 45

In the administration of either oxygen or 50 nitrous oxide gas, air may be given in any desired amount.

Another novel feature of my invention is the provision for the attachment of a cylinder for supplying an agent for the resuscitation or stimulation of respiration of a patient overcome by the administration of an anesthetic or anesthetics. 55

My invention further consists of novel means for preventing the freezing of the valves during long anesthesia. 60

It further consists of a novel construction and arrangement of devices forming a single apparatus and novel means for controlling said devices whereby the desired result may be obtained. 65

Other novel features of construction and advantage will hereinafter more clearly appear in the detailed description of my invention. 70

For the purpose of illustrating my invention, I have shown in the accompanying drawing one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described. 75 80

Figure 1 is a plan view, partly in section, of an anesthetizing and resuscitation apparatus embodying my invention.

Fig. 2 is an elevation, partly in section, of the wash bottle manifold. 85

Figs. 3 and 4 are end elevations, partly in section, of the wash bottle manifold.

Fig. 5 is a top plan view of a bottle cap.

Fig. 6 represents a top plan view of a heating pad and its adjuncts. 90

Fig. 7 is a broken view showing in proper relation the positive pressure bag, the two-way cock, the pharyngeal tube, the mixing chamber 47 and the mercury manometer of my apparatus. 95

Fig. 8 comprises detail sectional views of the two-way cock, the passage through the cock being closed in one view and open in the other. 100

Fig. 9 is a detail view of the mercury manometer *per se*.

Fig. 10 shows the rebreathing bag, the mouth piece, and the tubes complementary to the same.

Similar numerals of reference indicate corresponding parts in the figures.

Referring to the drawings.

1 designates a casing or body portion of an anesthetic and resuscitation apparatus embodying my invention, said casing having 10 within it a mixing chamber 2. The top of the casing 1 is provided with a heating pad 3 of any desired or conventional type, and for purpose of illustration, I have shown an electrically heated pad. The function of 15 this heating pad is to allow the administration of warm air or gas and to prevent the freezing of the valves.

4 designates a fitting, in threaded engagement with the body portion 1 and provided 20 at its inner end with an apertured cap 5 which is in threaded engagement with it. 6 designates a partition in the fitting, having a port 7 which is controlled by means of an inwardly-opening check valve 8, the stem of 25 which is guided in a sleeve 9 carried by a plate 10, which latter is provided with the ports 11. 12 designates a spring which tends to maintain the valve in closed position. The fitting 4 is provided with a 30 branch 13, which communicates with a regulating valve 14 of any desired or conventional type, which is in communication with the oxygen cylinder or a cylinder containing some other reviving agent, as desired, said 35 cylinder being adapted to be received in the yoke 16 and to be clamped in position by means of the clamping device 17. The fitting 4 is also provided with a branch 18 which is in communication with a regulating 40 valve 19, constructed in a similar manner to the regulating valve 14 and provided with a yoke 20 and clamping device 21, whereby the oxygen cylinder which communicates with the regulating valve 19 is clamped in position. 45

22 designates a fitting communicating with the mixing chamber 2 and constructed in a similar manner to the fitting 4 and provided with an inwardly opening check-valve 23, and the other features described as appurtenant to the fitting 4. The fitting 22 is provided with a plurality of branches, each of which is connected with a regulating valve, and as shown, one branch is connected with 50 a regulating valve 24, which communicates with a nitrous oxid gas cylinder which is secured in the yoke 25 and clamped in position by means of the clamping device 26. The other branch of the fitting 22 communicates 55 with a regulating valve 27, which latter carries a yoke 28 in which is adapted to be received a nitrous oxid gas cylinder which is clamped in position by means of the clamping device 29 and which is in communication 60

with the regulating valve 27. These valves 65 24 and 27 provide a separate and individual control for each nitrous oxid gas cylinder, thereby allowing any cylinder to be replaced during the operation without any interruption of anesthesia. 70

The check valve fittings 4 and 22 are connected at the top in any desired manner with pressure gages 80 and they are connected at the bottom by means of conduits 30 and 31 with a manually actuated stop cock 32 and a 75 needle valve 33, the fitting 4 being in communication with the stop cock 32, and the fitting 22 being in communication with the needle valve 33.

34 is a fitting communicating with the 80 mixing chamber 2 and adapted to be connected to the air pump, and is provided with an inwardly opening check-valve 35, preferably corresponding in construction to the check-valves 8 and 23. This air pump connection provides for the admixture of air either automatically or by a foot pump in any proportion and either warm or cold so that it can be used in ether or chloroform 85 anesthesia, either with or without gas, or for resuscitation.

36 designates a graduated stop cock in communication with the mixing chamber 2 and provided with an indicating arm or pointer 37 and calibrations 38, so that the position 95 of the valve may be visibly indicated. This stop cock 36 provides for controlling the amount of gas to the patient or for cutting the wash bottles off from the machine when it is desired to administer gas and oxygen 100 directly through conduits 30 and 31. 39 designates a needle valve communicating with the stop cock 32 and controlling the 105 flow of mixture to the wash bottle 40.

41 designates a needle valve controlling 110 the flow of the mixture to the wash bottle 42. 43 is a needle valve seating, as shown in Fig. 2, so as to cut off the manifold 44 when it is desired to use the wash bottle 45 to enable the operator to perceive the character 115 of the gas. In this case the wash bottle 45 is controlled directly through the needle valve 33. The needle valve 33 controls the passage of nitrous-oxid gas to the wash bottle 45, containing water, when the stop cock 36 is cut off, and when the cock 32 is closed and the needle valve 43 is opened the operator is enabled to perceive the character of the gas by viewing the sight feed bottles. The stop cock 32 provides for an emergency 120 supply of oxygen at any time and for direct oxygen connection to the manifold 44 when the stop cock 36 and the needle valve 43 are shut off. The wash bottle 45 contains water and the wash bottle 42 contains ether, thus providing for ascertainment of the character 125 of gas administered by the wash bottle method and at the same time allowing any

amount of the oxygen to bubble through the ether, thus giving any amount of ether desired.

46 designates a second manifold over the 5 wash bottles and this manifold, together with the manifold 44, provides an additional mixing chamber. 47 designates a mixing chamber communicating with the wash bottles, 40, 42 and 45. The mixing chamber 47 10 is provided with a slip joint hose and reducing fitting 48, which is adapted to be connected to the tubing leading to the rebreathing bag and thence to the mouthpiece. The said rebreathing bag is shown in Fig. 15 10 and numbered 70. It is connected at one end to a tube 71 adapted to be secured on the fitting 48 and is connected at its opposite end with an ordinary mouth piece 72. 49 20 designates a mercury manometer connected to the mixing chamber 47 in order to insure safety from over pressure and provide for positive pressure for use in resuscitation or in intra-tracheal anesthesia.

The relation of the wash bottles 40, 42 and 25 45 to the remainder of the apparatus will be readily understood by comparison of Figs. 1 to 4, when it is stated that the upper end of each bottle is connected through a tube 40^a with the mixing chamber 47 as shown in 30 Fig. 4 with reference to bottle 40 and in Fig. 3 with reference to bottle 45; also, that the lower end portion of the interior of each bottle is connected through a tube 40^b with the chamber formed by the alined manifolds 35 44 and 46. The mixing chamber 47 is disposed in parallel relation to the alined manifolds 44 and 46, Figs. 1, 3 and 4, and has no connection with said manifolds except through the bottles 40, 42 and 45. Communication 40 between the manifold 46 and the tube 40^b of bottle 45 is controlled by the needle valve 43; communication between the adjacent ends of the two manifolds 44-46 and the tube 40^b of bottle 42 is controlled 45 by the needle valve 41; and communication between the manifold 44 and the tube 40^b of the bottle 40 is controlled by the needle valve 39. As will be seen by comparison of Figs. 1, 2 and 3 the casing of the needle 50 valve 33 is connected at 60 with the casing of the valve 43 at a point between the seat of said valve 43 and the tube 40^b complementary to the bottle 45; also, that the casing of said valve 33 has its lower end 61 adapted for the connection of the conduit 31.

When the character of gas or mixture is ascertained by the wash bottle method and the nitrous oxide and oxygen pass through the conduits 30 and 31, the stop 60 cock 36 and the needle valve 43 are cut off. The wash bottles 40, 42 and 45 are wash or sight feed bottles to be used for water, ether or chloroform.

In accordance with my present invention,

I provide two distinct methods of regulating 65 and controlling the percentage of the gas mixture, namely, either by pressure gages or by sight feed bottles, and these can be used together or independently of each other. The percentage of ether or chloroform is 70 regulated alone with the wash bottle and its needle valve connection, thus permitting any degree of ether or chloroform mixture to the nitrous oxid or oxygen. By the use of an air pump, warm ether or chloroform vapor, 75 either separately or mixed, may be admitted.

In Fig. 7 I show an Elsburg positive pressure bag 60 connected through a tube 61 with the fitting 48 of the mixing chamber 47, and I also show a two-way valve 62 connected through a tube 63 with the bag 60, and through a tube 64 with a pharyngeal tube 65. The said valve 62 is also shown in detail in Fig. 8.

With the Elsburg positive pressure bag 85 60, two way valve 62 and pharyngeal tube 65 with the mercury manometer 49 to control the pressure, resuscitation can be accomplished with absolute safety and without the possibility of injury to the lungs. 90 When the said Elsburg positive pressure bag and its described appurtenances are to be used on my apparatus, the tube of the rebreathing bag before described is removed 95 from the fitting 48, and the tube at the opposite side of the Elsburg bag, with reference to the two way valve or cock and the pharyngeal tube thereof, is placed on the said fitting 48. The said Elsburg bag and its appurtenances are of the usual well 100 known construction and I have therefore deemed it unnecessary to illustrate the same. By the introduction of the intra-tracheal tube, safe-guarded by the mercury manometer, intra-tracheal aeration of the lungs can 105 be accomplished in asphyxia by using either air or oxygen or any percentage of them. By this technique, intra-tracheal anesthesia is easily administered, using gas or ether or 110 any combination of them.

It will be apparent from the foregoing that in accordance with my present invention, I provide in a single apparatus means to administer every form of inhalation anesthesia and also a resuscitation device for the continuous artificial aeration of the lungs. 115 I also provide a double method of estimating the percentages of the different gases, either of which methods may be used separately or both of them may be used in combination, as desired. The same apparatus may be employed for artificial respiration, either by oxygen, air, or any percentages of them in combination. The gas tanks may be changed 120 without interrupting the anesthesia and without any loss of gas. The air may be used in any proportion when using any form of anesthesia without any adjustment or at 125

tachment on the face piece for such purpose. The anesthesia may be interrupted and air employed to allow the patient to come as nearly out from the anesthetized condition 5 as desired, and without any change in the mechanism, anesthesia can be recommenced at will. Oxygen, nitrous oxid, gas, or air may be administered in any proportion.

It will now be apparent that I have devised a novel and useful anesthetizing and resuscitation apparatus which embodies the features of advantage enumerated as desirable in the statement of the invention and the above description, and while I have, in 10 the present instance, shown and described a preferred embodiment thereof which will give in practice satisfactory and reliable results, it is to be understood that the same 15 is susceptible of modification in various particulars without departing from the spirit or scope of the invention or sacrificing any of its advantages.

Having thus described my invention what I claim as new and desire to secure by Letters Patent, is:—

1. An apparatus of the character stated, comprising a casing having a mixing chamber, a valve controlled air inlet, a valve controlled gas inlet, and a valve controlled oxygen inlet, wash bottles in valve controlled communication with said mixing chamber, and a second mixing chamber in valve controlled communication with said wash bottles, a valve to control communication from 30 said oxygen inlet to said wash bottles, and a valve controlled connection from said gas inlet to said wash bottles.

2. An apparatus of the character stated, comprising a casing having a mixing chamber, a valve controlled air inlet, a valve controlled gas inlet, and a valve controlled oxygen inlet, wash bottles in valve controlled communication with said mixing chamber, a second mixing chamber in valve controlled 40 communication with said wash bottles, a valve to control communication from said oxygen inlet to said wash bottles, and a valve controlled connection from said gas inlet to said wash bottles.

45

oxygen inlet to said wash bottles, a valve controlled connection from said gas inlet to said wash bottles, and means to cut out a predetermined wash bottle.

50

3. An apparatus of the character stated, comprising a casing having a mixing chamber, a valve controlled air inlet, a valve controlled gas inlet, and a valve controlled oxygen inlet, wash bottles in valve controlled communication with said mixing chamber, a second mixing chamber in valve controlled communication with said wash bottles, a valve to control communication from said oxygen inlet to said wash bottles, a valve 60 controlled connection from said gas inlet to said wash bottles, and a mercury manometer communicating with said second mixing chamber.

4. An apparatus of the character stated, 65 a mixing chamber, means for supplying air under pressure to said chamber, valved means for supplying an anesthetic to the chamber, water bottles, valved means connecting the water bottles with said chamber, 70 a valved by-pass connection between the means for supplying anesthetic and one water-bottle, and a chamber connected with the water bottles and having means for connection with a patient.

75

5. An apparatus of the character stated, a mixing chamber, means for supplying air under pressure to said chamber, valved means for supplying an anesthetic to the chamber, water bottles, valved means connecting the water bottles with said chamber, 80 a valved by-pass connection between the means for supplying anesthetic and one water-bottle, and a chamber connected with the water bottles and having means for connection with a patient, and also having a mercury manometer.
